ABSTRACT OF THE DISCLOSURE

Membrane capillary exchangers including multiple countercurrent exchangers and the processes for making and using them are disclosed in the present application. The membrane capillary is produced by deposition onto an auxiliary core followed by bundling a plurality of the capillaries, introducing a means for holding into the ends of the cores, casting and hardening the means for holding to the ends of the capillaries, removing the mold and then removing the auxiliary cores from the interior of the membranes. The exchanger is operable in the chamber for dialysis liquid treatment.

The invention concerns a process for the production of a capillary exchanger as well as the resultant improved exchanger obtained by this process.

Capillary exchangers have many applications, e.g. as exchangers for gases or components of solutions, for heat exchange and the like.

Capillary exchangers are already known which, however, have various shortcomings. Above all, it is the end face zone of the capillaries of such an exchanger with the necessary end plates in which the capillaries must be mounted that is often defective. The shearing stress on the capillaries in the area of the end plates is substantial and readily leads to breakage. In addition, leakage which is difficult to control often occurs at the mounting of the capillaries in the end plates.

It is therefore a first object of the present invention to eliminate such defects and to produce such capillary exchanger apparatus in an industrially feasible process for mass production distinguished by excellent tensile strength and stability of the mounting in the end plates.

The preferred mode of the process according to the invention leads to improved capillary exchangers which, in addition to the above-mentioned advantages also has the further advantage of an especially favorable flow in the exchanger's interior. This advantage will be explained in detail further below.

The invention concerns primarily a process for the production of a membrane capillary exchanger having capillaries which are arranged side by side and spaced apart from each other, both ends of said capillaries being firmly embedded with their open end faces in holes of at least two holding walls, wherein each intracapillary space constitutes a passageway for a first liquid and the intercapillary space between the holding walls constitutes a passage for the flow of a second liquid and wherein each membrane capillary has been produced by the application, onto an auxiliary core consisting of a dissolvable or relatively easily fusible auxiliary substance, of at least one membrane layer, deposited from a solution of a substance capable of forming a membrane, or from a solution of an intermediary substance which is convertible into the final membrane substance, and, in the latter case, subsequent conversion into the final membrane substance, which process comprises (a) bundling a plurality of the membrane capillaries or intermediary product capillaries,

2

which capillaries contain the said auxiliary cores, while maintaining sufficient distances between the capillaries to allow the flow of the second liquid therethrough; and (b) introducing, in this arrangement the ends of the capillaries of said bundle into a holding means which is contained in a casting mold; (c) then pouring onto the holding means a layer of hardenable casting material which sealingly combines with the end zones of the capillaries; (d) hardening the resulting cast layer; then (e) removing the mold and the holding means contained therein from the interior of the membrane capillaries of intermediary substance the auxiliary cores, while preserving the outer layers constituting the membrane capillaries or the said intermediary substance capillaries.

In particular, the removal of the auxiliary core can be accomplished either by dissolving out the auxiliary core with a solvent which dissolves the said core but not the membrane capillary substance nor the said intermediary substance; or, in case the auxiliary core is made of a substance with a melting point below the melting point of the membrane capillary substance or the said intermediary substance, it can be melted out of the interior of the capillaries.

25 The finished capillary exchanger possesses then, as usual, an exchanging surface formed by the mantles of a plurality of hollow tubes or hollow threads which in the following are designated capillaries. These capillaries with their open end faces or the adjacent zones thereof are sealingly introduced or embedded in the end walls of the feed or collecting chambers and the exchange between the intracapillary interior space of the capillaries and the intercapillary space, i.e. the space surrounding the capillaries, can take place in one or in both directions.

30 In the exchangers produced according to the invention, the capillaries are sealingly embedded in their end face zones in the walls or parts of the walls of the feed chambers or of the hardened casting material forming the intercapillary space.

35 In the process according to the invention the above-mentioned membrane layers are applied to the auxiliary cores by lacquering or spraying them with drying and/or curable lacquers, casting resins or other resin forming liquid or pasty substances, such as, e.g., silicone rubber.

40 The application of one or preferably several coatings onto the auxiliary core is performed advantageously by using a solution of an intermediary substance which can be converted into the membrane substance, and the wall consisting of said intermediary substance is later converted by drying, curing or a suitable chemical treatment into the final substance forming the membrane capillary.

45 The dissolving or melting out of the auxiliary cores is preferably performed after the hardening of the layer or layers of casting material which form the walls of the intercapillary space or of a supply or collecting chamber or of a part of the wall of such a space.

50 According to the preferred embodiment of the process according to the invention, at least one of the two end face zones of each of the capillaries is coated on the outer circumference thereof with an auxiliary mantle, before the above-mentioned introduction into the holding means, thus improving the stability of the mounting of the capillaries in the layer of casting material.

55 65 Such auxiliary mantles are coatings applied to the capillaries, consisting, e.g., of lacquer, of casting resins capable of being hardened after application, or of deposits of metal, preferably having been produced electrolytically.

60 According to the invention, such auxiliary mantles substantially improve the adherence of the end face zones of the capillaries to the hardened layer of casting material surrounding them. This is, for example, the case when

the auxiliary mantles consist of silicone resins or metal. On the other hand these auxiliary mantles substantially reinforce the capillary end face zones in the vicinity of the hardened cast layer which surrounds them. Preferably, the auxiliary mantles consist of lacquer components such as acetyl cellulose, of hardened layers of casting resins such as epoxed resins, or of metal.

According to a further specific embodiment of the process according to the invention, when the layer of casting material is poured onto the holding means to engage the capillary end, a preferably prefabricated frame surrounding the entire bundle of capillaries is also placed on the holding means about the ends of the membrane capillaries or intermediary capillaries of said bundle so that said frame is also joined with said cast layer. This frame can be provided with appropriate projecting rims or indentations which form-lock with the final hardened cast layer so that the frame and the cast layer are very firmly joined.

In the process according to the invention, the capillaries are bundled either in a two-dimensional arrangement so that, e.g., a single layer of capillaries arranged parallel to each other is obtained, or preferably in a three-dimensional arrangement in a plurality of layers. The individual capillaries are first inserted into spacing tubes and then optionally conducted from these into spacers which remain in the bundle at least until the layer or layers of casting material have been poured onto the holding means, or still better, until the layer or layers of cast material have been hardened.

The bundle of the capillaries which are in the holding tubes or the spacers can then be treated at both ends thereof as described above for casting the layer or layers of material in the end face zones of the capillaries.

The capillary ends of one end of the capillary bundle is preferably inserted vertically into the holding means, which consists of an easily formable substance which is always or temporarily a liquid, a paste or a gelatinous mass preferably having a smooth surface, whereby this substance must be inert to the capillaries and to the casting material used for the cast layer. The capillary ends of the bundle are, e.g., dipped or inserted into the holding means.

After the drying or hardening of the cast layer, the holding means is removed by simple measures such as by heating, or by dissolving in suitable solvents.

According to the invention, the capillaries are arranged into a bundle by first arranging the capillaries in a preferably single layer, which can be compared with the warp of a fabric as used in the textile industry, then cutting off segments of such a single-layered arrangement of capillaries, and combining a plurality of such segments to a bundle consisting of a plurality of layers.

The operations described below, which primarily concern the end zones of capillaries which have already been combined, are preferably performed on a single layer or row of capillaries. They can, however, also be performed on the multilayered bundle of capillaries.

Many of these operations, such as, e.g., lacquering, hardening of hardenable coating substances, metallizing, etc. are more readily performed on single layers than on multi-layered bundles.

According to the invention, spacers can be used to arrange the capillaries in bundles, which spacers remain in the bundle when the end face zones of the capillaries are cast with the casting substance; the spacers can then be removed from the bundle or left in.

A specific embodiment of the invention comprises casting the spacers together with the casting material, preferably in a layer of casting material in which, at the same time, a prefabricated frame is fixed.

The invention further concerns a novel multiple countercurrent exchanger which can be produced according to the above-described process, comprising a casing; a bundle of tubes, preferably capillaries, in said casing,

5 which are essentially parallel to each other; two end walls in one of which walls the one end of the said bundle of tubes is fastened, while the other end of said bundle is fastened in the other wall, the tubes of said bundle having orifices on the outward sides of said end walls; a chamber containing the said bundle therein extending between the two end walls; an arrangement for charging the tube openings on one end of the said bundle with a first fluid and for removing the latter from the tube openings at the other end of the bundle, as well as inlet means 10 and outlet means, for the passage of a second fluid through the said chamber; an inset consisting of a plurality of walls forming between them a plurality of individual tubular channels being open at both ends, said inset being fastened in such a manner in the said chamber that through the interior of each of the said individual tubular channels there passes at least one of the said tubes, while in the zones of the interior of the said chamber adjacent to the said end walls there are free spaces, into which the orifices provided at both ends of the said individual tubular channels open, the said inlet means being connected with one of the free spaces and the said outlet means being connected with the other free space in the interior of the chamber.

15 In this multiple countercurrent exchanger according to the invention, the two end plates extend in two planes which are preferably not parallel with each other or which are curved, whereby the length of the tubes, in particular capillaries, of said bundle varies from one place to another.

20 The cross-section of each of the said individual channels of the inset preferably diminishes towards at least one of its two ends, in particular in the vicinity of that end of the inset which leads to the free space which is connected with the said fluid inlet means, the cross section being sufficiently narrow so that the second fluid introduced into the latter space is practically evenly distributed to all of the channels of the inset.

25 In a specific embodiment the said inset consists of a plurality of tubes being connected with each other in at least one zone, whereby the connection of the tubes of the inset, e.g., consists of at least one spacer. The walls of the inset can consist of a plurality of foils touching each other, at least a part of which are grooved or corrugated. On the other hand, the inset can consist of a block having individual channels formed by passages which run substantially parallel to each other.

30 In a preferred embodiment of the multiple countercurrent exchanger according to the invention, the tubes of the said bundle are thickened at at least one of the ends thereof, whereby the thickened portions extend through the end wall holding the respective ends of the tubes and reach into the interior of the individual channels of the inset surrounding the tubes.

35 The thickened ends of the tubes advantageously extend through the end wall located at the inlet side for the second fluid and into the interior of the individual channels surrounding the tubes, the cross section of which channels in the vicinity of the passage of the tubes therethrough is narrowed in such a way that the second fluid from the free space located at the inlet side is evenly distributed to all of the channels.

40 The individual channels are preferably provided with narrowed zones causing turbulence in the second fluid flowing therethrough, as well as other effects explained further below. The portions of the tubes which are within the channels can also be provided with narrowed zones, by means of which zones turbulence is caused in the first fluid flowing therethrough.

45 Embodiments of the invention with reference to the attached drawings illustrate the invention more in detail. For the sake of clarity, the drawings are in places distorted and out of proportion, they also contain fewer elements than in practice. Thus the number of capillaries in the single "warp beam" layer of capillaries can be several

thousand, the number of capillaries per exchanger bundle several hundred thousand.

In the drawings:

FIG. 1 shows in perspective a partial view of an apparatus for bundling the capillaries;

FIG. 2 shows the same apparatus in lateral section;

FIGS. 3 to 7 show various steps for the introduction of the capillary bundle into the spacers;

FIGS. 8 to 11 show the various steps for the application of a layer of casting material;

FIG. 12 shows a specific embodiment corresponding to FIG. 10;

FIGS. 13 to 15 show various embodiments and the use of spacers;

FIGS. 16 to 19 show the individual steps of modifications in the process after removal of the holding means;

FIGS. 20 to 23 show the application of a layer of casting material after auxiliary mantles have been applied to the end face zones of the capillaries;

FIGS. 24 to 29 show the corresponding steps when a frame is used;

FIG. 30 shows a preferred embodiment of a novel multiple countercurrent exchanger produced according to the invention;

FIG. 31 shows a specific construction of inset tubular channels for such an exchanger;

FIGS. 32, 33 and 34 show other modified embodiments of such an exchanger;

FIGS. 35, 35a, and 35b illustrate modification of the process according to the invention for the production of capillaries with unsymmetrical cross-sectional properties;

FIGS. 36 and 37 show arrangements for the production of capillaries according to FIGS. 35, 35a and 35b;

FIGS. 38a and 38b illustrate the assemblage of several such capillaries according to FIGS. 35, 35a and 35b; and

FIG. 39 illustrates the operative characteristics of a bundle of capillaries according to FIGS. 35, 35a and 35b when used for electrodialysis.

FIG. 1 shows such a "warp beam"-type of single-layer, side-by-side arrangement of capillaries 1 on a roller 2. This single layer arrangement of the capillaries is unrolled from this roller in the direction of the arrow 3, conveyed to a storage holder 4 and inserted into it. The storage holder 4 consists of a plurality of rows of bores 5, which for example can be formed by a corresponding arrangement of rows of tubes 6. Advantageously, each bore 5 corresponds to one capillary 1.

The introduction of the capillaries 1 into the storage holder 4 is preferably accomplished by filling one row at a time of the bores 5 with a layer of the capillaries 1. For this purpose the capillaries are led through a guide plate 7 provided with holes 5', which can be moved parallel to itself in the direction of the double arrow 8.

After one layer of capillaries has been inserted into the storage holder, the knife 9 (not shown in FIG. 1, see FIG. 2) cuts off this layer of capillaries at position 10.

After moving the guide plate 7 the distance of one row of bores, the process described for introducing the capillaries can be repeated. The layer of capillaries can be transported for the introduction into the storage holder by means of the pair of rollers 11 (also only shown in FIG. 2), which is accordingly driven intermittently in the direction of rotation of arrow 12.

FIG. 2 shows schematically a side view of the same apparatus as is shown in FIG. 1. In FIG. 1 only the front portion of the storage holder 4 is shown in perspective view, FIG. 2 shows its whole length. In both figures the lower row of the bores 5 are already filled with capillaries 1. The capillaries 1 are shown as lines. For clarity, the same linear representation of the capillaries has been chosen for FIGS. 3 to 22, 28 and 34.

Preferably the bores 5 are open at both ends of the storage holder 4 and the length of the storage holder is less than the length of the capillary segments, so that

these, as shown in FIG. 3, can protrude a short distance from both ends of the storage holder.

Furthermore, it is suggested that the rear ends 13 of the bores 5 or the tubes 6 are tapered or bent inwardly so that their rear orifices are narrower than their front orifices.

After the storage holder 4 has been completely filled with capillary segments 1, as shown in FIG. 3, spacers 14, consisting, for instance, of one or more woven pieces, the apertures of which are of the same size or larger than the diameter of the capillaries 1, while the distance between the apertures corresponds to the spacing of the bores of the storage holder, which spacers are located at one end of the storage holder, are appropriately brought into position (FIG. 4), advantageously at the end at which the tapered ends 13 of the bores are to be found.

In FIG. 4 the following process step is illustrated: the capillaries 1 are inserted by the pusher 15 through the storage holder and the front ends thereof are pushed into the spacers 14 to be in frictional engagement with the latter. Then all of the capillaries are drawn with the aid of the spacers 14 to the left in FIG. 6, i.e. out of the storage holder; at the same time or subsequently the spacers are distributed over the entire length of the bundle of capillaries until the latter are finally borne only by the spacers 14, namely, after the capillaries have been completely withdrawn from the storage holder (FIG. 7). These operations can be performed by hand or these movements can also be carried out automatically by known mechanical means (not shown). It is also possible to place the capillaries directly into the spacers without the intermediary use of a storage holder.

FIGS. 8 to 11 show the subsequent operations to which the capillary bundle is then subjected. In FIG. 8 this bundle is placed with the capillaries in vertical position above a layer of a holding means or agent 17 having an even and smooth surface, which has been poured into a trough 16. The lower ends of the capillaries are dipped or inserted into this layer of holding agent (FIG. 9). Then, as shown in FIG. 10, a layer 18 of casting material is poured onto the surface of the holding layer 17 and between the capillaries, and the cast layer is then hardened in the mold constituted by the surface of the holding agent 17 and the walls of trough 16. After this hardening process, or also during it, the capillary bundle together with the said poured-on and hardened layer 18 of cast material is withdrawn from the holding means 17 (FIG. 11).

After these operations have been completed, the other end of the capillary bundle can also be provided with a layer of hardened casting material in the same manner as described above and illustrated in FIGS. 8 to 11, by rotating the bundle by 180° and repeating these steps.

FIG. 12 shows a modification of this process leading to another form of the exchanger, wherein the capillaries are closer to each other in their end face zone than in the adjacent zone of the exchanger. If, on the other hand, it is desirable to have the capillaries equally spaced apart, in the zone in which they are embedded in the terminal face walls as well as in all other zones of the exchanger, the process steps shown in FIGS. 8 to 11 will afford this result. An embodiment of a capillary exchanger according to the invention in which the capillaries are arranged to meet this requirement illustrates a preferred feature of the invention.

The spacers 14 can, for example, remain or be removed after the production of the layers of hardened cast material 18. This can be removed by pulling out the spacers or by dissolving them in a solvent.

Spacers can be, for instance, perforated sheets or woven material, as shown in section in FIG. 13, or combs the teeth of which have been laid across each other, as shown in FIGS. 14a and 14b (separated position) and FIG. 14 (crossed position, in which the capillaries 1 have been inserted). In some of the apertures of the spacers accord-

ing to FIGS. 13 and 14, capillaries 1 of the capillary bundle have been inserted in a manner corresponding to FIG. 7.

FIG. 15 shows an embodiment of the spacers 14 constructed as an inset unit; these spacers are formed by flat walls 114 and corrugated walls 115, which are joined together in such a way that channels 116 are formed between them in which the capillaries 101 are placed.

The FIGS. 30 and 31 contain further modifications of spacers 214 and 314 serving as inset unit.

FIG. 30 shows a cross-section of a multiple counter-current exchanger according to the invention which consists of an outer casing containing an arrangement of six single-layered rows 210a to 210f of capillaries mounted therein, which rows are made up of capillaries which, from the center row outward, are of diminishing length, each of said rows consisting of one layer of capillaries 201 which at their ends 201a and 201b, as shown in detail in FIG. 23, are sealingly embedded in auxiliary coatings 234 which have been fused or joined to form lamellae. These auxiliary coatings are applied instead of the auxiliary mantles 20 mentioned above, as shown in FIG. 23, e.g. by subsequently applying lacquer to the capillaries 1, a single coat at a time, and preferably choosing substances or mixtures of substances which dissolve onto the membrane coatings 35; an inset unit 236 consisting of walls forming channels 206 can also be used. The inset unit 236 also comprises two terminal layers formed by fusion of the end portions of the channel walls, one of which layers, 237, in FIG. 30, is plane and the other one, 238, is convex.

The lamellae 234 of the single-layered rows are joined with each other by intermediary layers of casting material 218 and thus form, on the one end, the plane end plate 239 and, on the other, the convex end wall 240 which is preferably less curved than the terminal layer 238 formed by the ends of the channel walls.

The chamber 242 formed between the terminal layer 238 and the end wall 240, having a concave-convex lens-shaped inner space, thus has a smaller cross section in its central zone than at its outer zones. When feeding fluid F_2 into the chamber 242 through the inlets 243, 244, the fluid is thus caused to circulate about the central zone within the chamber, which fact substantially contributes to an even, radially symmetric entry of the fluid into the tubular channels 206.

The chamber 245 formed between the terminal layer 237 and the end plate 239 is provided with outlets 246 for the fluid which exits upwardly out of the tubular channels 206, only one of which is shown in FIG. 30. Above the end plate 239, in the casing 221, there is provided an inlet chamber 247 having a central inlet opening 248 for fluid F_1 which is to be passed through the capillaries 201.

The tubular channels 206 are narrowed in the vicinity of their open ends at 206a and 206b, which contributes to an even distribution of the fluid F_2 and by obstruction causes a slowing down of the flow rate of the fluid F_2 through the tubular channels 206.

The fluid F_1 leaving the end wall 240 at the lower open end of each capillary 201 is collected in a basin 249 forming the bottom of the exchanger and can be discharged therefrom through a discharge pipe 250 preferably provided with a discharge cock.

In FIG. 31 the tubular channels 314 are not only narrowed near their open ends but also in a plurality of intermediary zones 314a to 314e. Besides further slowing down the flow rate of the fluid F_2 through the channels, these narrowed passages primarily serve to center the capillaries 301.

In FIGS. 32 and 33, examples of other embodiments of multiple counter-current exchangers are shown. In the embodiment of FIG. 32, the capillaries 401 decrease in length from the side wall 402 to the opposite side wall 403; thus the end walls 439 and 440 extend toward the

side wall 403 at an acute angle with each other; while in FIG. 33, the end walls 539 and 540 also form an angle with each other, but the capillaries 501, in contrast to the modification in FIG. 33, are not straight but curved.

Finally, FIG. 34 shows, in perspective view, purely schematically, the construction of a plurality of single layers of capillaries 601 combined into a bundle, in which in the one direction each individual layer of capillaries increases in length from the outside towards the interior, and in the other direction the capillaries of the various layers increase in length from the side walls 602 and 603 towards the middle of the bundle compared with the corresponding capillaries belonging to the next adjacent row towards the outside.

FIG. 16 shows in enlarged form the same process stage as is shown in FIG. 11, in which the capillaries have been pulled out of the holding means or agent 17. Some of this holding agent may still adhere to the lower ends of the capillaries. This residue can be removed e.g. by dissolving in an inert solvent or by heating. The cleaned condition is illustrated on an enlarged scale in FIG. 17.

According to a further embodiment of the invention, one or several additional layers 19 (FIG. 18) or 19' (FIG. 18') can be applied onto the upper or lower side of the hardened layer of casting material 18, e.g., by application of a drying lacquer or a curable casting resin or elastomer.

Finally, FIG. 19 illustrates a further modification of the treatment of the end face zones on the capillaries. The underside of the hardened layer of casting material together with the protruding ends of the capillaries can be finished by machining operations (e.g. by milling or smoothing), so that the capillaries terminate flush with the hardened layer of casting material.

The FIGS. 20 to 23 show a preferred embodiment of the process for forming a hardened layer of casting material with the capillary ends penetrating it and thus also an elaboration of the exchanger design.

Here the capillary ends are strengthened by auxiliary mantles 20 before the formation of the hardened layer of casting material 18. These auxiliary mantles can be formed, for example, by dipping the entire multilayered arrangement of capillary ends according to FIG. 20 into a lacquer or a casting resin and subsequently drying and/or curing the coatings, at the dipped-in capillary ends, or also by deposition of metal with or without the aid of electrolytic processes, the latter, for example, by silver reduction after the capillary ends have been made conductive. The auxiliary mantles 20 can be so short, that, as shown in FIG. 22 (which corresponds to FIG. 19), they do not protrude beyond the hardened layer of casting material 18, or, as shown in FIG. 21 (which corresponds to FIG. 10), they protrude beyond the layer of casting material 18. In FIG. 23, the end face zones of the capillaries provided with auxiliary coatings are touching one another, an arrangement by which, especially in the case of reinforcement with a layer of metal, a particularly high stability is achieved.

Corresponding to FIG. 10, FIG. 24 illustrates a further modification of the process according to the invention. Here, a prefabricated frame 21 is simultaneously embedded into the layer of casting material 18 at the time of the production of this layer. Preferably the frame 21 is provided with a projecting rim 22, so that the layer of casting material 18 is fastened onto the inward side of the frame by form-locking serration. The frame can be joined with the opposite frame and spaced from it by distance bolts, as can be seen in FIGS. 26 and 27 which represent side view and top view of a complete exchanger.

Analogously, FIGS. 28 and 29 show an exchanger having a non-rectangular frame.

In FIG. 26, in addition, there is shown a pair of supply or collecting chambers 24, one connected to each side of the exchanger, which supply chambers assure the collective supply and removal of the intracapillary substance

to and from all of the capillaries through the feed pipes 25.

The walls of the capillaries of the exchanger produced according to the invention can be formed of one or several layers. The membrane coatings forming the walls of the capillaries can consist of inorganic, organic or metallic materials. Organic membranes, can, for example, consist of cellulose hydrate. They can be produced, e.g., by the process described in French Pat. No. 1,539,221, issued on Aug. 31, 1967, which corresponds to South African Pat. 675,172.

The capillaries can also be produced as coated layers on auxiliary cores, these auxiliary cores being prefabricated solid threads and wires, or threads and wires which are themselves capillaries, said cores being composed of substances which are relatively easily soluble and/or relatively easily fusible compared with the membrane coatings or intermediary substances, and said cores have been removed by dissolving and/or melting them out of the coatings forming the capillaries proper. The coating layer on the auxiliary core can, for example, be produced by lacquering or spraying the auxiliary core with drying and/or hardening lacquers, casting resins or other cross-linking, fluid or pasty substances such as silicone rubber. The auxiliary cores can, for example, consist of polystyrene, polyvinyl acetate or wax; the specific solvent therefor can, e.g., be trichloroethane, benzine or the like.

The dissolving out and/or melting out of the coating layer can, according to the invention, be performed simultaneously on all of the capillaries, preferably after the formation of the hardened layer of casting material 18.

The diameter of the capillaries is preferably in the range of from 0.1 to 5 mm.; the distances between them in the capillary bundle of the exchanger have similar dimensions.

The material of the hardened layer of casting material 18 consists of substances which have been hardened or cross-linked by thermal, drying and/or chemical processes, which substances were capable of being cast or were in the form of pastes before these processes were effected, i.e. such substances are, for example, acetyl cellulose, epoxid resins, polyester resins, polymethacrylates, single and multiple-component silicone rubbers, pastes of metal/synthetic materials, etc.

As holding agent 17, for example, gelatin/water mixtures, waxes and silicone resins can be employed. Examples of solvents which are inert towards the casting material and the capillaries, and which can be employed to dissolve the holding agent are, e.g., water, alcohol, benzine and the like. The material of the frame 21 and the distance bolts 23 can consist of metal or synthetic material (such as polypropylene).

The material of the spacers 14 can consist of synthetic material, metal and the like; when these spacers are to be subsequently removed from the capillary bundle by dissolving operations, the spacers (in particular woven material) can be made of monofilament polyalcohol threads, which dissolve in water.

The exchangers of the invention serve, e.g., as dialysers (e.g. for the separation of materials such as the separation of lower molecular portions from protein solutions, or for blood dialysis), for water extraction according to the principles of reversed osmosis, for refrigeration, or for sterilization, e.g. for substances such as milk which are conducted through the intracapillary space and can be heated there in an exact dose for a short time and optionally cooled, by introducing into the intercapillary space the appropriate heating and cooling agents.

It is also possible to use such exchangers for distillation processes, e.g. for the vacuum-multiflash process for the desalting of sea water, the sea water being introduced through the capillaries and the condensation of the steam taking place in the intercapillary vacuum.

Finally, the invention also concerns another embodiment

ment of the exchanger which can be produced according to the invention, which embodiment is suited for electro-dialysis, e.g. for the desalting of sea water. This embodiment for desalting can also be used with a magnetic field.

For the performance of this modification for the production of exchangers for the last-mentioned purpose, starting capillaries which still contain an auxiliary core are used, the membrane walls of which capillaries have unsymmetrical properties in respect to the cross section thereof. This means that, e.g., one half of the wall of an individual capillary is more ionically selective than the other half, or that the one half of the wall is anionically selective and the other half is cationically selective. In this case, the spacers must be so constituted that they fasten the capillaries to prevent rotation thereof, e.g. in relation to the tubular channels of an exchanger inset unit. This fixation is achieved, e.g., by gluing the capillaries with the individual cells or tubular channels of the spacer inset or also at the intersection of the laminated or latticed spacers with the capillaries.

In this connection, the invention also concerns the production of the last-mentioned kind of "unsymmetrical" capillaries suitable for use in exchangers, as well as the fixing thereof in appropriately constructed spacers or insets.

The production of these capillaries is performed according to the invention so that, analogously to the process mentioned above for the production of coating layers on prefabricated auxiliary cores, more than one substance is applied as a coating layer on the auxiliary cores in order to obtain unsymmetrical capillaries, and subsequently, preferably after bundling such coated cores in a plurality of layers, the auxiliary cores are dissolved out and/or melted out of these coating layers to form the capillaries proper.

Here again, solid threads, solid wires, or preferably, however, capillaries of relatively easily soluble and/or relatively fusible substances such as polystyrene, polyvinyl acetate, wax and the like can be used as auxiliary cores.

The auxiliary cores can be dissolved out of the capillaries formed by their coatings, e.g. using trichloroethane or benzine, and optionally liquified by heating, and removed from their coatings by means of pressure or centrifuging.

The auxiliary cores can, for example, be coated by applying a first lacquering substance to one half of the core by means of rollers and then, after drying or curing by chemical and/or thermal means, treating the opposite side (180° rotation about the longitudinal capillary axis) of the auxiliary core with another lacquering substance in the same manner. The two lacquering substances of the half coating layers contain, according to the invention, differing dry components with differing properties, such as anionic and cationic selective film forming substances.

According to the invention this half-sided application can be repeated several times; it is also possible either preceding or following these applications to apply a complete coating of another lacquer (e.g. acetyl cellulose and modifications thereof), which, moreover, can be subjected to a subsequent chemical treatment (e.g. saponification to cellulose hydrate). The coating operation can be performed continuously on a single dimensional arrangement of the auxiliary cores in rows (warp-like). It is also possible, at the same time, to place spacers across the auxiliary cores which have been coated and to spot-join these, e.g., using glue. Such spacers can be threads which are laid across the coated cores.

The FIGS. 35 to 39 illustrate this more in detail:

FIG. 35 shows in cross section an unsymmetrical capillary. Here it consists of only two halves formed by two different substances, one of which, 26, having, e.g., anionically selective properties and the other, 27, cationically selective properties.

FIG. 35 shows, as mentioned above, only two asymmetrically arranged half mantles, which are sealingly and

11

firmly joined with each other at their line of contact. According to the invention, such a capillary can, however, also have other inner and outer layers which are also arranged symmetrically around the entire circumference thereof.

FIG. 35a shows the same capillary as in FIG. 35, but still in the state of its production. 28 is a capillary type of auxiliary core onto which the half mantles 26 and 27 have been applied according to the invention, and which core is to be subsequently removed. Analogously, FIG. 35b shows a solid wire (or solid thread) 28' as auxiliary core.

FIGS. 36 and 37 show an example for the production of the unsymmetrical capillaries according to the invention. The auxiliary cores 28 (in this case shown as capillaries) are wound in linear arrangement on the roller 29 and pass the two rollers systems 31 in the direction of the arrow 30. These roller systems consist of a lacquering trough 31', a plurality of distributing rollers 31" and the lacquering roller 31'''.

The first lacquering roller 31''' is shown again in FIG. 36 in section. The auxiliary capillaries 28 move over said lacquering roller in grooves in which the lacquer component 32 is applied by the distributing rollers, thus being lacquered on one half, and then pass through the drying unit 33. Then the auxiliary capillaries 28 which have been lacquered on one side and dried, pass through the second lacquering unit 31 which operates in the same manner as the first one, but transposed by 180°, since the roller 31''' operates from above. After passing the second drying unit 33, the single dimensional layer of auxiliary capillaries which have now been lacquered with two half mantles can be wound on the drum 34. Either before or after winding, the threads 29 (see FIGS. 38a and 38b) can be laid across the capillary coatings and, for example, be spot-fixed with heaps of material 30.

Of course, symmetrical capillaries can also be produced starting with a single-layered row of auxiliary cores, e.g. using the apparatus of FIGS. 36 and 37.

FIG. 38a shows in section, FIG. 38b in top view, the arrangement according to the invention of a plurality (three in the figures) of unsymmetrical capillaries corresponding to FIG. 35, which are spot-joined with spacers 29, e.g. by heaps of glue 30. This arrangement and stable combination assures that all of the capillaries are aligned in the same direction in relation to their unsymmetrical structure.

The intracapillary space of all of the capillaries provided with the above-described developments, can be connected to distributing chambers. It is, however, also within the scope of the invention that the unsymmetrical capillaries as described and their two-way arrangement can also be connected to distributing chambers by conventional and known methods.

By bundling the capillary "warps" according to FIGS. 38a and 38b, a system is obtained as shown in FIG. 39, which can, e.g., be used as an electrodialytically operating system, by means of which the intracapillary space 32 of all the capillaries is brought into reaction with the intercapillary space 33 between the capillaries within an electric field generated by the electrodes 41+ and 41-.

Therefore, the invention also concerns a process for performing electrodialytic separations by means of a membrane capillary exchanger, comprising applying an electrostatic field to the intracapillary space of hollow tubes or hollow threads (named capillaries in the following), arranged side by side and fixed against rotation, and at the same time to the intercapillary space between this arrangement of capillaries, passing a first fluid through the intracapillary space, and passing a second fluid through the intercapillary space, the mantles of the capillaries being produced from more than one differently ionically selective substance in such a manner that these differing substances are arranged for each capillary mantle non-symmetrically in respect to the cross section of the capillary

12

and that all of the capillary mantles are oriented in the same direction and fixed against rotation.

We claim:

1. A membrane capillary exchanger comprising,
  - (a) a casing having sidewalls and fluid inlet and outlet means;
  - (b) a bundle of membrane capillary tubes which tubes are each open at both ends, said tubes being in spaced and substantially parallel relationship to each other, and to said sidewalls of said casing;
  - (c) each capillary bearing, in at least one end zone of said bundle transverse to the extension of said capillary tubes therein, an auxiliary mantle sealingly bonded to a narrow region of the surface of the capillary tube and leaving the two openings at the ends of the latter as well as the major wall portion of the tube outside said transverse end zone free;
  - (d) a layer of cast material compatible with and sealingly adhering to the auxiliary mantles of all of the capillaries of said bundle as well as to the sidewalls of said casing in said transverse zone, thus constituting a transverse separating wall inside said casing;
  - (e) means for admitting a fluid from said inlet means in the openings of the capillary tubes at one end of said bundles; and
  - (f) means for conducting said fluid from the openings of the capillary tubes at the other end of said bundle into said outlet means.

2. A membrane capillary exchanger as defined in claim 1, wherein there are provided two of said transverse separating walls in said casing, one nearer a first end region and the other nearer an opposite end region of said casing, and wherein said inlet means open into the interspace between the wall of said casing in said first end region and the adjacent transverse separating wall, while said outlet means open to the outside from the interspace between the wall of said casing in said second end region and the transverse separating wall adjacent to the latter.

3. A membrane capillary exchanger as defined in claim 2, wherein each of said two transverse separating walls extend in planes each of which is not parallel with the other or is curved.

4. A membrane capillary exchanger as defined in claim 1, wherein distancing means are provided between the capillaries outside said transverse zone or zones in which said transverse separating wall or walls extend, thereby holding said capillaries in spaced relationship relative to each other outside said zone or zones.

5. A membrane capillary exchanger as defined in claim 4, wherein there are provided two of said transverse separating walls in said casing, one nearer a first end region and the other nearer the opposite end region of said casing, and wherein said distancing means comprise a plurality of tubular ducts each of which surrounds at least one of said capillary tubes in the region intermediate said two transverse separating walls, and wherein said inlet means open into the interspace between the wall of said casing in said first end region and the adjacent transverse separating wall, while said outlet means open to the outside from the interspace between the wall of said casing in said second end region and the transverse separating wall adjacent to the latter.

6. A membrane capillary exchanger as defined in claim 5, wherein the rims of the tubular ducts facing toward one of said transverse separating walls are connected with each other and with the adjacent sidewalls of the casing to form a third inner transverse wall in said casing, and the rims of the tubular ducts facing toward the other transverse separating wall are connected with each other to form a fourth inner transverse wall in said casing, and wherein first fluid circulating means are connected to the chamber between said first transverse separating wall and said third inner transverse wall, and second fluid circulating means are connected to the chamber between said other transverse separating wall and said fourth inner transverse wall.

13

7. A membrane capillary exchanger as defined in claim 6, wherein said first transverse separating wall and the adjacent third inner transverse wall are plane, and at least one of the second transverse separating wall and the adjacent fourth inner transverse wall are of convex shape having the same or different curvature, when both are convex. 5

8. A membrane capillary exchanger as defined in claim 7, wherein the convex transverse wall or walls in said casing have their apex at a greater distance from the plane transverse walls than their peripheral zones. 10

9. A membrane capillary exchanger as defined in claim 6, wherein both said first and second transverse separating walls are of convex shape with their apices toward the adjacent end region of said casing. 15

10. A membrane capillary exchanger as defined in claim 5, wherein said distancing means comprise a plurality of foils touching each other, at least part of which foils are grooved or corrugated. 20

11. A membrane capillary exchanger as defined in claim 4, wherein said distancing means comprises a block having individual ducts therein extending substantially parallel to each other. 25

12. A membrane capillary exchanger as defined in claim 5, wherein each of said tubular ducts have at least one zone of narrowed cross section whereby the flow of fluid therethrough is rendered turbulent. 25

13. A membrane capillary exchanger as defined in claim 1, wherein each of said capillary tubes (201) comprise cellulose hydrate, the auxiliary mantles (234) comprise a material selected from the group consisting of lacquer, acetyl cellulose, casting resin and metal, and the cast material forming said layer or layers (218) in said transverse zone or zones (239, 240) is selected from the group consisting of hardened acetyl cellulose, epoxy resin, polyester resin, polymethacrylate, silicone rubber and paste of metal, and synthetic material. 30

14. Electrodialytic liquid treatment apparatus comprising—

- (a) a chamber having sidewalls;
- (b) inlet and outlet means for the passage of a first fluid through said chamber;
- (c) a bundle of membrane capillary tubes which tubes are each open at both ends, said tubes being in spaced

14

and substantially parallel relationship to each other, and to said sidewalls of said chamber;

- (d) each capillary bearing, in at least one end zone of said bundle transverse to the extension of said capillary tubes therein, an auxiliary mantle sealingly bonded to a narrow region of the surface of the capillary tube and leaving the two openings at the ends of the latter as well as the major wall portion of the tube outside said transverse end zone free;
- (e) a layer of cast material compatible with and seemingly adhering to the auxiliary mantles of all of the capillaries of said bundle as well as to the sidewalls of said casing in said transverse zone, thus constituting a transverse separating wall inside said chamber;
- (f) means for admitting a second fluid from an inlet means into the openings of the capillary tubes at one end of said bundles; and
- (g) means for conducting said second fluid from the openings of the capillary tubes at the other end of said bundle into an outlet means.
- (h) means for applying an electrostatic field across said chamber and to the intercapillary space between the arrangement of capillaries.
